(57) **CLAIM**

The ornamental design for a swappable headset computer with reversible display and temple supports, as shown and described.

DESCRIPTION

FIG. 1 is front perspective view of a swappable headset computer with reversible display and temple supports illustrating the Applicant's new design.

FIG. 2 is a front view of the swappable headset computer.

FIG. 3 is a right view of the swappable headset computer.

FIG. 4 is a top view of the swappable headset computer.

FIG. 5 is a back view of the swappable headset computer.

FIG. 6 is a left view of the swappable headset computer; and, FIG. 7 is a bottom view of the swappable headset computer. The broken lines shown in the drawings form no part of the claimed design.
